UNITED STATES PATENT OFFICE.

BENTLEY A. PLIMPTON, OF VICTOR, NEW YORK.

STRAIN-INSULATOR.

1,266,711.

Specification of Letters Patent. Patented May 21, 1918.

Application filed January 25, 1917. Serial No. 144,347.

To all whom it may concern:

Be it known that I, BENTLEY A. PLIMPTON, of Victor, in the county of Ontario and State of New York, have invented certain new and useful Improvements in Strain-Insulators; and I do hereby declare the following to be a full, clear, and exact description of the same, reference being had to the accompanying drawings, forming a part of this specification, and to the reference characters marked thereon.

The invention has for its object to improve the structure of strain insulators, more particularly with a view to affording a cementless connection between a metal cap, stud or connecting member, and the insulating portion or member of the usual type of strain insulating unit. A further object of the invention is to afford a connection that will be sufficiently strong to withstand any of the strains to which such an insulator is usually subjected, also to entirely eliminate the use of cement in joining a cap, stud or connecting member, and the insulating portion, and further to provide an economical construction that can be readily made and assembled without excessive cost. To these and other ends the invention consists in certain improvements and combinations of parts, all as will be hereinafter more fully pointed out in the claims at the end of the specification.

In the drawings:

Figure 1 is a side elevation of an insulator constructed in accordance with my invention;

Fig. 2 is an enlarged side view showing the metal cap in section, about to be assembled on the insulating unit;

Fig. 3 is a sectional view showing the position of the parts after the cap is locked on;

Fig. 4 is a horizontal sectional view on the line 4^a—4^a of Fig. 3;

Fig. 5 is a vertical sectional view taken centrally of the insulator, and

Fig. 6 is a horizontal sectional view on the line 6^a—6^a of Fig. 5.

Similar reference characters throughout the several views indicate the same parts.

According to the construction herein disclosed, which illustrates a possible embodiment for carrying out my invention, there is shown a usual type of strain insulator embodying a metal cap 1 and an insulating portion or member which includes the flar-

ing portion or skirt 2 and the head or top portion 3. The top portion 3 has formed thereon what I have termed a thread, indicated by 4 and extending partially around the insulating unit and terminating at its lower edge in a locking shoulder or ledge 5, which serves to engage and hold in place a locking member carried by the cap 1, as will now be described.

The cap 1 is provided at its lower portion with an inturned flange 6 and carries a locking member having one end in fixed relation and the other end in movable relation therewith to permit separation of the ends, and threading the locking member on the insulating portion. With this in view I preferably employ a split ring designated by 7. One end of the said ring has an outwardly extending projection or lug 8 which engages an opening or recess 9 in the cap, while the other end of the ring is movable so as to permit the parts to assume the relative position shown in Fig. 2, where the free end of the locking member is engaging the upper side of the thread 4 and the fixed end lies between the opposite ends of the thread 4 and is about to pass under the shoulder 5. This is the first position that is assumed when the cap is assembled upon the insulating portion and by turning the cap to the right from the position shown in Fig. 2, the locking member is carried with it until it is entirely under the thread 4 and locked in place by the shoulder 5. After this relative positioning of the parts is accomplished it is practically impossible to remove the cap from the insulating portion except by breaking one of the parts. When the locking member is in locked relation, it rests upon the flange 6 and is located between it and the lower edge of the thread 4, as shown clearly in Fig. 3.

In the usual operation of devices of this character, it is common to employ several insulators which are interconnected and support a conductor, for which purpose the cap 1 carries a lug or extension 10 having an opening 11 that receives a pin 12 coöperating with a connecting member 13 on the adjacent insulator unit. Each insulating portion is formed hollow to receive a stud or connecting member 13, the same being also hollow as shown in Fig. 5, and provided with the openings 14 in which the pin 12 is located. It is necessary to retain the connecting member or sleeve 13 within the hol-

low portion of the insulating portion and to this end the latter is provided with a shoulder 15 which receives a plurality of locking devices and thereby prevents the connecting member 13 from being withdrawn. The connecting member or sleeve 13 is provided with a series of openings 16 within which are located the locking devices 17. These latter are in the form of blocks which are freely movable in the openings and are provided with inclined or beveled surfaces 18 to engage the shoulder 15 aforesaid. The locking devices 17 are prevented from withdrawal away from the locking shoulder by means of a sleeve or thimble 19 located within the connecting member and held in place by any suitable retaining means. In assembling the parts just described, the connecting member is first inserted within the hollow portion of the insulator, and the locking devices 17 are then inserted in the connecting member and forced through the openings 16 by any suitable instrument or tool for the purpose, until they engage the shoulder 15. The thimble or sleeve 19 is then dropped or positioned within the connecting member with its outer surface engaging the inner ends of the locking devices 17. The thimble 19 is held in place preferably by inserting a cement filling material 20 therewithin, as shown in Fig. 5.

I claim as my invention:

1. The combination with an insulating portion having a thread thereon terminating in a locking shoulder, of a cap coöperating with the insulating portion and carrying a locking member that is brought into engagement with said shoulder by being threaded on the insulating portion.
2. The combination with an insulating portion having a thread thereon terminating in a locking shoulder, of a cap carrying a movable locking member that is brought into engagement with said shoulder by being threaded on the insulating portion, the movable relation of the locking member permitting it to be threaded upon the insulating portion and moved into locking engagement under the shoulder.
3. The combination with an insulating portion having a thread thereon, of a cap attached to the insulating portion and carry-

ing a locking member having one end in fixed relation and the other end in movable relation with the cap to permit the locking member to be threaded upon the insulating portion and to lockingly engage under said thread. 55

4. The combination with an insulating portion having a thread thereon terminating in a shoulder, of a cap secured upon the insulating portion and carrying a locking member in the form of a split ring having one end in fixed relation and its opposite end in movable relation with the cap to permit threading the locking member upon the insulating portion and bringing it into locked relation with said shoulder. 60 65

5. The combination with an insulating portion having a locking shoulder extending partially therearound, of a cap secured upon the insulating portion and carrying a locking member in the form of a split ring, one end of which engages a recess in the cap while the opposite end is freely movable to 70 permit the locking member to be threaded upon the insulating portion by initially placing the free end of the locking member beneath said shoulder and turning the cap until the entire locking member is disposed 75 beneath the shoulder. 80

6. The combination with a hollow insulating portion having a locking shoulder therewithin, of a hollow connecting member arranged within the insulating portion and 85 having a plurality of openings, a plurality of locking devices movable within said openings and having engagement with the aforesaid locking shoulder, retaining means engaging the locking devices to prevent their 90 withdrawal from the locking shoulder, and a cementitious filling medium within the connecting member engaging the retaining means and preventing withdrawal of the latter. 95

7. The combination with an insulating portion having a locking shoulder extending partially therearound, of a cap secured upon the insulating portion and carrying a movable locking member adapted to be brought 100 into locking relation with the shoulder by turning the cap on the insulating portion.

BENTLEY A. PLIMPTON.
